UNITED STATES PATENT OFFICE.

DANIEL T. DENTON, OF TOWER MINES, MINNESOTA.

LIFTING-CAGE FOR MINES.

SPECIFICATION forming part of Letters Patent No. 395,041, dated December 25, 1888.

Application filed May 26, 1888. Serial No. 275,195. (No model.)

To all whom it may concern:

Be it known that I, DANIEL T. DENTON, of Tower Mines, in the county of St. Louis and State of Minnesota, have invented a new and 5 Improved Lifting-Cage for Mines, of which the following is a full, clear, and exact description.

The object of the invention is to provide a new and improved lifting-cage specially adapted 10 for mines, on which the cars are firmly held in position when raised or lowered in the mine-shaft, and which also permits of running the cars on or off the cage easily.

The invention consists of a cage provided 15 with rails having depressions in which the car-wheels rest and of arms for raising the wheels out of the depressions.

The invention also consists of parts and details and combinations of the same, as will be 20 fully described hereinafter, and then pointed out in the claims.

Reference is to be had to the accompanying drawings, forming a part of this specification, in which similar letters of reference indicate 25 corresponding parts in all the figures.

Figure 1 is a plan view, partly in section, of the improvement. Fig. 2 is a sectional side elevation of the same on the line *x x* of Fig. 1. Fig. 3 is a vertical cross-section of the 30 same on the line *y y* of Fig. 2, and Fig. 4 is a detail sectional view of the rock-shaft.

The improved lifting-cage A is provided with the usual platform, B, on which are held the rails C and C', each provided near one end 35 with a segmental depression, C², into which depressions fit one pair of the wheels of the car to be carried by the lifting-cage A. At the sides of the rails C and C' are held the arms D and D', respectively pivoted at D² to 40 the rails C and C', and preferably connected with each other at their outer ends by a transversely-extending bar, D³, passing under the rails C and C', which are provided for this purpose with notches C³, as shown in Fig. 2.

When the car is moved onto the cage, the 45 wheels of the car travel on the rails C and C', and one set of wheels passes into the depressions C² of the said rails, whereby the car is firmly held in position on the cage. The latter is now moved up or down in the shaft of the mine, and when it reaches either the surface or the bottom of the shaft the arms D 50

and D' are raised by suitable means, so that the said arms engage the projecting parts of the treads of the wheels, thereby lifting said 55 wheels out of the depressions C² until the lower parts of the respective car-wheels are in line with the tops of the rails C and C'. The car is then run off of the cage in the usual manner.

The means of raising the arms D and D' 60 may be of any desirable construction, preferably, however, the one shown in Figs. 2 and 3, in which the platform B of the cage A is engaged by the arms E, secured to a shaft, F, 65 mounted in suitable bearings at the bottom of the shaft of the mine or at the top of the same. The shaft F is provided with an additional set of arms or prongs, G, somewhat longer than the arms E and adapted to engage the 70 transverse bar D³, connecting the arms D and D' with each other. Thus, when the car descends and the shaft F stands in the position shown in Figs. 2 and 3, the platform B of the 75 lifting-cage rests on top of the arms E, and the longer arms, G, having previously engaged the cross-bar D³, move the arms D and D' upward, so that the car-wheels are lifted out of the depressions C², as before described. A lever, weight, or other device may be employed for operating the shaft F, so as to assume the position necessary for raising the arms D and D' automatically whenever necessary.

When the car is run off of the cage, the shaft 85 F is turned so that the arms E and G swing outward and the arms D and D' assume their former position—that is, the tops of the said arms D and D' are somewhat below the bottoms of the depressions C².

Having thus fully described my invention, I 90 claim as new and desire to secure by Letters Patent—

1. In a lifting-cage for mines, the combination, with rails having depressions in which 95 the car-wheels are adapted to rest, of arms held at the sides of the said rails for raising the wheels out of the said depressions, substantially as shown and described.

2. In a lifting-cage, the combination, with 100 the cage-platform, of rails held on the said platform and having depressions in which are adapted to rest the car-wheels, and arms pivotally connected with the said rails for raising

the wheels out of the said depressions, substantially as shown and described.

3. In a lifting-cage, the combination, with the cage-platform, of rails held on the said platform and having depressions in which the car-wheels are adapted to rest, arms pivotally connected with the said rails for raising the wheels out of the said depressions, and a transverse bar connecting the outer ends of the said arms with each other, substantially as shown and described.

4. In a lifting-cage, the combination, with rails having depressions and arms pivotally connected to the said rails, of a rock-shaft and arms secured to the said rock-shaft and adapted to engage the said pivoted arms, substantially as shown and described. 15

DANIEL T. DENTON.
